UNITED STATES PATENT OFFICE.

WILLIAM H. SMITH, OF PORT LAVACA, TEXAS.

GATE.

SPECIFICATION forming part of Letters Patent No. 447,374, dated March 3, 1891.

Application filed June 9, 1890. Serial No. 354,853. (No model.)

To all whom it may concern:

Be it known that I, WILLIAM H. SMITH, a citizen of the United States, residing at Port Lavaca, in the county of Calhoun, in the State of Texas, have invented a new and useful Improvement in Suspended Roller-Gates, of which the following is a specification.

My invention relates to improvements in the construction of self-closing roller-gates, by which greater simplicity is attained and the operation of the gate is much facilitated.

The gate is a structure hanging and sliding by means of rollers on an inclined cross-bar, and so connected by ropes and pulleys to stationary posts that a person approaching it on horseback or in a vehicle may easily open the gate (without dismounting) by pulling the rope, and on releasing the rope the gate will close automatically.

The drawing is a perspective view of the gate.

In the specification similar letters of reference indicate corresponding parts in the drawing.

A represents the ground, in which the posts b' , b^2 , b^3 , b^4 , and b^5 are firmly driven. Posts b^4 , b^5 , and b^2 have the inclined cross-bar c (which may be either of round or flat bar-iron) secured to them, as shown. The bar is bent at either end to such an angle as may be required by the inclination of said bar. The ends are let in and riveted or bolted to posts b^4 and b^2 , and the center of the bar is supported by post b^5 and secured thereon by a staple y . The posts are so located that if connected by lines they would form a square, rhomboid, or diamond, according to the requirements of the traffic passing through the gate, with post b^5 in the center of the same.

The gate proper consists, essentially, of two uprights d d' , to which the rollers d^2 d^3 are fastened and secured on the cross-bar by means of pins g . The rope or chain i is fastened to one end of the gate and passes through the double pulley f on the post b^2 , and also through the hanging (single) pulleys o of posts b' and b^3 . To the other end of the gate is attached the rope h , passing over a pulley in post b^4 and carrying the weight k .

The posts b' and b^3 have catch-springs l fastened on them to hold the rope i attached to the gate and keep the same opened any desired length of time. When the rope is drawn

from underneath the catch-spring, the gate will close automatically by its own gravitation on the inclined cross-bar on which the hanging rollers of the gate are running and also by the weight k . It will be observed that the pull-rope is arranged in a bisected triangle with its ends terminating in upright d' . The upright d has a part cut out of its foot end to clear the axle and hub of any carriage passing through, so that the axle cannot strike the gate and possibly break it. In the foot end of the posts b^4 and b^5 are driven right-angled guards m and n , in which the lower end of the gate slides to guard against stock or wind swinging the gate.

The operation of the gate is as follows: By reference to the drawing it will be seen that a person desiring to pass the gate and approaching it from the direction of post b' takes hold of that part of the rope forming the base of the bisected triangle, pulls it and holds it until the gate is passed. The pull on the rope will react on the pulley on post b' , also on one of the pulleys f on post b^2 , and finally on the terminal in upright d' . By these means the gate opens in the direction of the double pulley on post b^2 , and will close itself by means of gravitation as soon as the person releases the rope. When it is desirable that the gate should be kept open long enough for a wagon-train or a herd of cattle to pass through, a person in the lead opens the gate and secures it in that position by fastening the rope under the catch-spring, and a person in the rear, after passing the gate, pulls the rope from underneath the catch-spring and the gate will close, as herebefore described.

Having thus described my invention, I claim as new and desire to secure by Letters Patent—

The combination, with a gate suspended on an inclined track c , of a single pull-rope passing around suitable pulleys on posts b' , b^2 , and b^3 and secured at both ends to the inner upright d' of the gate, so as to form a bisected triangle, and catch-springs l on the front of the posts b' and b^3 , substantially as shown and described.

WILLIAM H. SMITH.
